FINISHING MACHINE

Gustave A. Carlson, Detroit, Mich.

Application August 23, 1935, Serial No. 37,525

17 Claims. (Cl. 51—103)

My invention relates to improvements in a finishing machine in which the object to be finished is actuated to move between and in contact with a pair of moving members; and the objects 5 of my improvements are, first, to provide a finishing machine in which the object to be finished is engaged by a pair of moving members and is actuated to move by the pair of moving members between them; second, to provide a finishing 10 machine having a member with a conical surface for engaging the object to be finished and to actuate the object with a feeding movement past a finishing wheel; third, to provide a frustum shaped member for engaging the object to be finished and having adjusting means whereby the 15 frustum shaped member may be adjusted to have its axis located at different positions below the axis of the object being finished to provide varying rates of speed with which the frustum shaped member will actuate the object past a finishing member; fourth, to provide a finishing machine with a frustum member having means for 20 adjusting its position in a vertical plane and in a horizontal plane relative to the member being finished; fifth, to provide a finishing machine with a pair of wheel members for engaging opposite sides of the member being finished, the pair of wheel members being adapted to finish the member and actuate the member with a feed movement; sixth, to provide a finishing machine having 25 its mechanism, for actuating the member being finished with a feed movement, mounted on a pair of slide members; seventh, to provide a finishing machine with means for supporting the member being finished, this means being adjustably supported independently of the finishing mechanism to vary the supporting position of the supporting means relative to the member being finished; eighth, to provide a finishing machine 30 having a feed actuating mechanism together with its driving mechanism movably supported on a pair of slide members, one supported on the other and each being adapted for movement in planes at right angles to one another; ninth, to provide a finishing machine having an anti-friction mechanism for rollably engaging the member being finished; tenth, to provide a 35 finishing machine having a resiliently actuated mechanism rollably engaging the member being finished; eleventh, to provide a finishing machine having means for positioning the member to be finished and to further allow the finishing member to engage the member to be finished with a relative light contact or engagement to provide 40 for a minimum amount of material being removed

from the member in the finishing operation; twelfth, to provide a finishing machine having means for engaging and positioning the member to be finished and incorporating an anti-friction bearing assembly for the engaging member; and 5 thirteenth, to provide a finishing machine having a rollably mounted member engaging the member being finished to provide uniformity of pressure of the member being finished against the finishing member.

10 I attain these objects by the mechanism illustrated in the accompanying drawings, in which—

Figure 1 is a front elevation of the finishing machine; Fig. 2, a plan view of the finishing machine; Fig. 3, an end view of the finishing machine; Fig. 4, a sectional view taken on the line 4—4, Fig. 1; Fig. 5, a sectional view taken on the line 5—5, Fig. 2; Fig. 6, a partial end view of the feed mechanism disclosing a pulley member without its enclosing housing; Fig. 7, a sectional view of the frustum member support mechanism taken on the line 7—7, Fig. 3; Fig. 8, an end view of the resiliently actuated means for engaging and positioning the member to be finished in relation to the frustum member; Fig. 9, a plan view of the mechanism disclosed in Fig. 8; and Fig. 10, a sectional view of the anti-friction assembly unit utilized in the mechanism disclosed in Figs. 8 and 9, said sectional view being taken on the line 10—10, Fig. 8.

20 Similar numerals refer to similar parts throughout the several views.

The finishing machine as herein described is so-called because of its adaptability for finishing round objects such as tubes, and shafts, a tube 25 being disclosed at 1, said tube 1 being finished by polishing, or buffing the outside cylindrical surface thereof, said finishing being similar to that disclosed in my United States application for Letters Patent, Serial No. 703,662, filed December 22, 1933, now Patent No. 2,059,724, dated Nov. 3, 1936.

30 It will be readily noted that my finishing machine as hereinafter described will thus be particularly adapted for any such similar finishing operations requiring the grinding, polishing, or buffing of cylindrical surfaces.

The grinding machine will be provided with a base 2 upon which is suitably mounted and supported the housing structure 3 which extends upwardly therefrom and is constructed as an enclosing housing for the electric motor assembly A and the driving mechanism operatively connected therewith as hereinafter more fully disclosed.

35 The housing structure 3 will form an enclosure 50

55

extending entirely around the electric motor assembly A and will be provided with an open portion 4 at its lower end and located at the rear of the machine, said open portion 4 extending 5 downwardly below the point 4A to the base 2 as disclosed in Fig. 3 and providing necessary circulation of air to and from the housing structure 3, said circulation of air being caused more or less by the operation of the electric motor assembly 10 A and its operatively connected mechanism. Also the wall 5 at the rear of the housing structure 3 may be provided with an open portion 5A extending between its sides and if desired for its full length to facilitate the assembly of the electric motor assembly A and its operative mechanism. The cover 6 is used to cover such suitable opening 5A in the wall 5 to close said opening in the wall 5, the cover 6 being suitably secured to the housing structure 3 by the screws 7.

20 On the upper wall 8 of the housing structure 3 is suitably mounted the housing member 9, said housing member 9 being provided with suitable flanges to facilitate its securement to the upper wall 8. The housing member 9 is provided with 25 the boss portions 14 and 15 in which are respectively retained and assembled the bearing assemblies 16 and 17. The shaft 20 extends through the housing member 9 and is revolvably supported in the bearing assemblies 16 and 17. The 30 shaft 20 is provided with a shouldered portion 21 on which is mounted the driven pulley 22, the driven pulley 22 being secured on the shoulder portion 21 by the nuts 23. The driven pulley 22 is provided with the hub portion 24 which is 35 spaced from the bearing assembly 16 by the spacer 25. The pulley 22 is provided with a pair of grooves 26 which are frictionally engaged by the driving belts 27. The driving belts 27 engage and are driven by frictional contact in the grooves 40 28 of the driving pulley 29 which is suitably secured against the collar 30 which in turn is supported on the driving shaft 31 of the electric motor assembly A, the pulley 29 being secured thereon by the nut 32.

45 The electric motor assembly A is provided with the flange or foot portions 33 which are supported on and are secured to the bracket member 34 by the bolts 35 and the nuts 36. The bracket member 34 may be provided with the bosses 37 which 50 are pivotally supported relative to the center of the shaft 160, the shaft 160 having its ends extended and supported within the side walls of the housing structure 3, the shaft 160 being located endwise by the collars 161 which are secured 55 to the shaft 160 and engage the inside surfaces of the housing structure 3. The shaft 162 is similarly supported in the side walls of the housing structure 3 and is located endwise by the collars 163. The member 164 is suitably secured around 60 the shaft 162 and extends through the bracket member 34 and is secured thereto by the nuts 165, the nuts 165 being movably mounted on the member 164 to enable the bracket member 34 to be adjustably and pivotally moved relative to the 65 shaft 160 to provide for the adjustment of the tension of the belts 27.

The shaft 20 is further provided with a shoulder portion 38 on which is suitably secured the buffing, polishing, or finishing wheel or member 39, 70 the wheel or member 39 being suitably secured to the shoulder portion 38 as to be driven therewith. Also the buffing wheel 39 may be further secured by the clamping washers 40 and 41, the clamping washers 40 and 41 being secured in their clamping 75 position by being pulled up tight by the nut

42 which may threadably engage the shoulder portion 38, the clamping washer 41 being thereby pulled tight against the spacer member 43 which is interposed between the clamping washer 41 and the bearing assembly 17.

5 It is thus to be noted that the electric motor assembly A will drive the driving pulley 29 which in turn through the medium of the drive belts 27 will drive the driven pulley 22 which will in turn revolvably operate the shaft 20 together with 10 the buffing wheel 39, which is secured thereto as above described.

The buffing wheel may be suitably chosen in accordance with the kind of finishing surface desired to be obtained on the tube 1 and the buffing 15 wheel may be conventionally constructed from discs of cotton or woolen fabric or other suitable material adapted for carrying the desired abrasive powders which are applied with the proper bonding material to the fabric of the discs. Obviously the type of buffing wheel will vary some- 20 what with the type of finish desired whether obtained by a grinding, buffing or polishing opera- 25 tion.

Across the front of the machine is suitably 25 mounted the bracket or flange member 44 which is connected with the web portion 45 by which the flange member 44 is secured to the front surface of the housing structure 3 and to the base 2. The flange member 44 is further provided with the 30 ledge, boss or housing portion 47 which is provided with the bore 46 in which extends the shaft or stud member 48 which may revolvably engage the bore 46 of the boss or housing portion 47.

It is also to be understood that the flange por- 35 tion 44, the web portion 45, and the boss or housing portion 47 may be incorporated in a sepa- 40 rate casting or housing which may be supported on a floor or similar surface, independently of the base 2 when such installation is more economical or is desired for other reasons.

The boss 47 extends outwardly from the front 45 face of the housing structure 3 and is provided with the clamp boss 51 which is provided with a slot 52 therethrough for providing a clamp struc- 50 ture that can be secured in its clamping position for fixedly securing the shaft 48 in its ad- justed positions, the shaft 48 being adjustably moved by turning the nut member 53 which 55 threadably engages the shaft 48 and is mounted on the surface 54A of the boss 47, the nut mem- 60 ber 53 being provided with the openings 55 to permit a bar or shaft to be inserted therein for a 65 lever or handle member.

The bracket or housing 54 may be formed in- 65 tegrally with the shaft or stud member 48 as disclosed, or the shaft or stud member 48 may be 70 constructed separately and suitably secured to the bracket or housing 54 to support same. The bracket 54 is provided with the slideway or V's 60 56 in which is movably mounted the slide 57 which is adapted to operate in a horizontal 75 plane, the gib 58, together with the screws 59, being utilized in a conventional way to adjust- 80 ably take up wear between the slideway 56 and the slide 57. The slide 57 is secured to the hori- 85 zontal flange 60 of the bracket 62 by the screws 63. The bracket 62 is provided with the vertical or upstanding flange 64 which is provided with the slideway or V's 65 in which is movably 90 mounted the slide 66 which is adapted to operate in a vertical plane and in a direction substan- 95 tially at right angles to the direction of move- ment of the slide 57.

The slide 57 is provided with a chamber 67 into 75

which extends the boss 68 suitably secured to the bracket 54, the chamber 67 providing operating clearance for the slide 57 relative to the boss 68. The shaft 69 is revolvably mounted in the slide 57 and threadably engages the boss 68 and provides means whereby the slide 57 may be slidably moved in the slideway 56 by the revolvble movement of the handwheel 70 suitably mounted on and secured to the shaft 69. If desired the 10 slide 66 may be provided with a gib between it and the slideway 65 and actuated by screws similar to the construction disclosed relative to the slide 57 and slideway 56.

The slide 66 is provided with the recess or 15 chamber 71 while the flange 64 is provided with the chamber 72 into which extends the boss 73 which is suitably secured to the vertical slide 66, the chamber 72 providing operating clearance for the boss 73 of the slide 66.

20 The flange 64 is provided with a boss 74 which has a bore 75 which forms a bearing for the shaft 76 which is revolvably mounted therein and retained against longitudinal motion by the collar 77 suitably secured to the shaft 76 and 25 engaging the inner end surface of the boss 74, the handwheel 78 being suitably secured at the upper end of the shaft 76, as by threadably engaging the shaft 76, and by riveting as at 79, the handwheel 78 being adapted to suitably engage 30 the outer end surface of the boss 74, the shaft 76 being further provided with the portion 80 which threadably engages the boss 73 to actuate the slide 66.

It is to be understood that the slide 66 will 35 be fitted sufficiently snug in the slideway 65 so that the weight of the slide 66 and its operatively supported mechanism will not be fully supported by the portion 80 of the shaft 76.

The bracket 62 may be suitably reinforced by 40 the ribs 62A and 62B. The slide 66 is further provided with a table portion 83 which is further provided with the slideway or V's 87 in which is movably mounted the slide 85.

The table portion 83 of the slide 66 is suitably 45 provided with the nut portion 82 which is suitably secured thereto and is engaged by the shaft 81 which may be threadably connected therewith. The shaft 81 is further connected with the hand wheel 84 provided with the handle 84A, the shaft 81 being revolvably mounted in the slide 85 which is movably mounted in the slideway or V's 87 of the table portion 83, the table portion 83 being provided with the recess or chamber 88 providing operating clearance over 50 the nut portion 82.

It will thus be noted that a revolving motion 55 of the hand wheel 84 will thus slidably move the slide 85 relative to the table portion 83 of the slide 66. The gib 89 may be installed between the slide 85 and the slideway 87 to take up wear, the gib 89 being adjustably actuated by the screws 90.

The bracket 91 is provided with the flange 92 which may be suitably secured to the slide 85 60 and is adapted to move with the slide 85 when operated by the hand wheel 84 as above described. The bracket 91 is provided with the boss 92A which in turn is provided with the clamping bosses 93 through which extend the 65 clamping screw 94, the boss 92A being suitably slotted longitudinally through its length and through the clamping bosses 93 to permit the boss 92A to be clamped around the extension portion 95 of the housing 96 through which 70 extends the shaft 97 which is revolvably sup-

ported in the bearing assembly 98 and 99. The housing 96 is provided with the enlarged portion 100 in which rotates the worm gear 101 which is suitably mounted on the shaft 97, the enlarged portion 100 of the housing 96 being provided with the bosses 102 in which is mounted the shaft 103 on which is secured the worm 104, the worm 104 operatively engaging and driving the worm gear 101. 5

The enlarged portion 100 of the housing 96 is 10 provided with the cover 105 which is secured thereto by the screws 106. The pulleys 107, 108 and 109 may be individually mounted or mounted as a unit on the shaft 103 and suitably secured thereto so as to revolve therewith. The pulleys 15 107, 108 and 109 are adapted to be engaged by the belt 110 which frictionally engages and is driven by the pulleys 111, 112 and 113 as disclosed. The pulleys 111, 112 and 113 may be mounted individually or mounted as a unit on the 20 shaft 112A of the electric motor assembly B which is provided with the flange or foot portions 114 which permit the securement of the electric motor assembly B to the table or bracket 115 by the screws 116. Also it is to be noted that the housing 96 will be provided with the upright portion 117 in which is suitably mounted the table or bracket member 118, the table member 118 being secured by the screws 119A. The table 118 is provided with the ears 119 which form a yoke 30 portion for supporting the shaft 120 on which is pivotally supported the table 115 by means of its ear portions 121 which engage the shaft 120. 35

It will thus be noted that the plate 115 may be pivotally moved around the center of the 40 shaft 120 to provide means for shifting the operating center of the electric motor assembly B to provide the proper driving tension on the driving belt 110. The table 118 is further provided with the ears 122 which form a yoke portion in 45 which is mounted the shaft 123 which provides for the pivotal motion for the adjusting member 124 which extends through the plate 115 and may be located in various adjusting positions by the nuts 125.

At the inner end of the shaft 97 is mounted the frustum member 126 or member provided with the conical surface 127, the conical surface 127 engaging the tubular member 1.

The frustum member 126 is provided with the 50 hub portion 128 to facilitate its securement so as to be driven by the shaft 97. The frustum member 126 may be constructed with an outer member 129 which is preferably constructed of leather or similar material, the member 129 forming the 55 portion of the frustum 126 which is provided with the conical surface 127.

It is to be noted that as the electric motor assembly B operates and drives the pulleys 111, 112 and 113, the driving belt 110 will in turn operatively drive the pulleys 107, 108 and 109 which will in turn drive the shaft 103 together with its worm 104 which will in turn operatively drive the worm gear 101 which will rotate the shaft 97 together with the frustum member 126 and its 60 member 129 having the conical face 127. 65

It is now to be noted that the tube 1 will be supported in the V portion formed by the members 130 and 131 which are each provided with the angular portions 132 to provide the above 70 mentioned V portion in which the tube 1 rests. The members 130 and 131 will be oppositely disposed about and secured to the plate or member 133. The plate member 133 will be supported on the flange 134 of the boss or flange portion 135. 75

The boss portion 135 is provided with the slot 136 through which extends the bolt 137 which is mounted in the boss portion 138 of the lever member 139. The boss portion 138 is provided with the boss 140 through which extends the set screw 141 which contacts the boss portion 135 and forms a reaction member for holding the member 135 in its adjusted position on the lever member 139, the member 135 thus being supported by the set screw 141 against movement caused by the buffing wheel 39 when the buffing wheel 39 operatively engages the tube 1, the buffing wheel 39 being operated in the direction as indicated by the arrow 142 in Fig. 3.

In order to further adjust the position of the plate 133 in its assembled position on the lever member 139, the lever member 139 is provided with the boss portion 143 which is pivotally mounted on the shaft 144, the shaft 144 being secured in the boss 145 of the bracket 62 by the pin 146, the lever member 139 being secured on the shaft 144 by the nut 147. The lever member 139 is provided with the ear portions 148 which form a yoke member on the lever member 139, the ear portions 148 providing support for the set screws 149 which are adapted to contact the lever 150 of the member 151 which is pivotally supported on the shaft 152 which is secured in the boss 153 of the bracket 62, the shaft 152 being secured therein by the pin 154.

It is to be noted that after the set screws 149 are adjusted to their desired position, the lever 150 will be clamped therebetween, the set screws 149 being secured in their adjusted position by the lock nuts 155. The member 151 is pivotally supported on the shaft 152 and to further secure the member 151 in its adjusted position for holding the lever portion 150 in its adjusted position and in engagement with the screws 149, the bracket 62 is provided with the arm 152A to which is secured the boss 153 in which is mounted the set screw 156 which in turn is locked in its adjusted position by the nut 157. The set screw 156 contacts with the lever portion 150 which forms a portion of the member 151. The set screw 156 thus absorbs any reaction due to the tendency of the lever member 139 to move from its adjusted position relative to the member 151. The member 151 may be further secured on the shaft 152 by the nut 159.

The housing 173 may be suitably supported to enclose the pulleys 107, 108 and 109 together with the pulleys 111, 112, and 113 and the belt 110, the housing 173 being closed by the cover 174 which is secured by the stud 175 and the wing nut 176.

It is to be noted that the member 133 will extend sufficiently on each side of the buffing wheel 39 to properly support the tube 1. The additional members 170 and 171 are each provided with the members 130 and 131 having the portions 132 for forming the above mentioned V portions for supporting the tube 1.

In operation it is to be noted that when the plate or member 133 is utilized as disclosed in Fig. 4, the plate or member 133 will be located in between the angular portions 132 which are in contact with the tube 1 at its underside, the plate or member 133 being located substantially in vertical alignment with the axis of the tube 1.

When the buffing wheel 39 is operated in the direction of the arrow 142 in Fig. 3, the tube 1 will be forced down into the V portion of the members 132. At the same time the frustum member 126 will be operated in the direction of the arrow 172 as disclosed in Fig. 1, the conical

surface 127 of the frustum member 126 operatively engaging the outer surface of the tube 1.

When the axis of the frustum member 126 is located below the axis of the tube 1, the tube 1 will be located approximately on the horizontal center or axis of the buffing wheel 39 and above the axis of the frustum member 126.

When the frustum member 126 is being operated in the direction of the arrow 172 as disclosed in Fig. 1 and with the side of its conical surface 127 in contact with the outer surface of the tube 1, the outer surfaces of the tube 1 will thus contact with the conical surface 127 at a point slightly above the axis of the frustum member 126 and to the right of the axis of the frustum member 126 as viewed in Figs. 1 and 2, the axis of the frustum member 126 being located at an angle relative to the axis of the tube 1 and the axis of the buffing wheel 39, the above mentioned inclination of the axis of the frustum member 126 being dictated by the angle of the conical surface 127.

It is now to be especially noted that with the movement of the frustum member 126 as above described and in contact with the tube 1 that the tube 1 will be gradually moved to the left relative to the buffing wheel 39, as viewed in Figs. 1 and 2, the speed of the longitudinal movement of the tube 1, which corresponds to its feeding speed, being dictated obviously by the position of the axis of the frustum member 126 below the axis of the tube 1. In other words, as the axis of the frustum member 126 is lowered below the axis of the tube 1, the speed at which the tube 1 will move longitudinally past the buffing wheel 39 will be increased as the frictional point of contact of the outer surface of the tube 1 with the conical surface 127 of the frustum member 126 is thus adjusted above the axis of the frustum member 126, the above mentioned feeding speed being increased as the point of contact between the tube 1 and the conical surface 127 approaches a vertical center through the axis of the frustum member 126.

The tube 1 will be revolved by frictional contact with the wheel 39 in the V portions 132, the revolving motion of the wheel 39 in the direction of the arrow 142, Fig. 3, tending to always force the tube 1 downwardly into the V portions 132. Also the frustum member 126 by contacting the outer surface of the tube 1 will provide a frictional or reaction member to maintain the tube 1 in the V portions 132 and thus prevent the tube 1 from being forced out of the V portions 132 due to any horizontal force component which is developed by frictional contact with the wheel 39.

It is also to be noted that the wheel 39 will be operated at a considerably higher speed than the speed at which the frustum member 126 is operated, the speed of the frustum member 126 being designated by the required feeding speed of the tube 1 past the wheel 39, the feeding speed of the tube 1 being further designated by the position of the axis of the frustum member 126 relative to the axis of the tube 1 as above described.

It is also to be noted that whereas a belt mechanism may be used in place of the wheel 39, such belt mechanism forming the finishing means in some machines as used conventionally at the present time, I have found that the wheel member such as 39 used in conjunction with a frustum member such as 126 of my invention constitutes a much more economical and efficient

mechanism than those used heretofore in finishing machines.

Where it is desirable to remove a minimum amount of stock or material from the member 1 and consequent relatively light engagement or contact of the finishing member 39 with the member 1 is necessitated, I utilize auxiliary means for rollably engaging and contacting the member 1 which relieves the finishing member 39 from the necessity of positioning and maintaining the member 1 against the frustum member 126 and in the members 130 and 131 and provides uniformity of pressure of the tube 1 against its finishing member.

15 This auxiliary mechanism is disclosed as being utilized on the finishing machine equipped with the members 130 and 131 for supporting the tube 1 as disclosed in Figs. 1, 2 and 3 and with which it may be used advantageously to secure uniformity of pressure of the tube 1 against and in engagement with the frustum member 126. Also the auxiliary mechanism is disclosed more in detail in Figs. 8, 9 and 10 and in conjunction with a plate 133 for supporting the tube 1 which may 20 be used in place of the members 130 and 131 when desired.

Also it is to be understood that the auxiliary mechanism although disclosed as being used in conjunction with a frustum member, is especially 30 adapted for use with other kinds of finishing members such as belts, wheels, or similar means used for finishing purposes.

This auxiliary mechanism comprises the brackets or members 180 which are each provided with the portions 181 which extend through the plate 133 and are threadably engaged and secured by the nuts 182.

The brackets 180 are each provided with bores 183 in which is rotatably mounted the shaft 184 which is provided with the bent or upturned portion 185 which extends through and upon which is slidably mounted the bracket 186 in which is fixedly mounted the key 187 which engages the keyway 188 of the portion 185.

45 The bracket 186 is provided with the boss portions 189 which are slotted to enable the boss portions 189 to be clamped in any selected and adjusted position on the portion 185 by the screw 190.

50 The bracket 186 is provided with the bore 191 through which extends the portion 192 of the stud 193, the portion 192 being threadably engaged and secured in the bore 191 by the nut 194. The stud 193 is provided with the cylindrical portion 195 which fits the bore 196 of the inner race 197 of a conventional anti-friction bearing unit or assembly C which is provided with the outer race 198 and the ball members 199 between said race members 197 and 198. The stud 193 is 55 provided with the head 200 which retains the bearing assembly on the cylindrical portion 195, the bracket 186 being offset, as at 201, to clear the outer race 198.

The bracket 202 is suitably secured to the plate 65 133 as by welding or similar means and is provided with the bore 203 through which extends the stud 206. The bracket 215 is provided with a bore for receiving the shaft 184 and is further provided with the boss portions 204 which are 70 slotted to permit the bracket 215 to be clamped and secured to the shaft 184 by the screw 205. The stud 206 is provided with the ball end 207 which extends within the slot 208 and is swivelly or pivotally secured therein by the pin 209.

75 The spring or resilient member 212 surrounds

the shank of the stud 206 and is retained thereon by the thumb or wing nut 213 which threadably engages the shank of the stud 206, the washers 214 being interposed between the spring 212 and the flange 211 and also between the spring 212 and the wing nut 213.

In operation the spring 212 will tend to pull or pivotally move the bracket 215, about the axis of the shaft 184, toward the flange 211 of the bracket 202, thus causing the shaft 184 together with its upturned portion 185 and the bracket 186 to be pulled or pivotally moved toward the member 1, thus causing the outer race 198 of the bearing assembly C to rotatably engage the member 1 with any desired friction as selected by the position of the wing nut 213, on the shank of the stud 206, the thrust of the outer race 198 against the member 1 maintaining the member 1 between and in the V portion of the flanges 132 of the members 130 or on the plate or member 133 and against the frustum member 126 or similar finishing member, thus allowing the finishing member 39 to be set in engagement with the member 1 with any desired frictional contact and maintaining uniformity of pressure of the tube 1 against a finishing member and obtaining any desired feed movement of the tube 1.

When the auxiliary means, as above described, is used to maintain the member 1 in its position during the finishing operation, it will be desirable to position the bearing assembly C opposite the thrust or contacting surface of the frustum member 128 or similar finishing member or in other words within the area of contact of the frustum member 128 or similar finishing member and the member 1 to be finished, this arrangement of the bearing assembly C and a frustum member being disclosed in Fig. 9.

I claim:

1. In a machine for finishing a cylindrical member, the combination of a housing structure providing an enclosed chamber, a shaft revolvably mounted on said housing structure, an electric motor assembly suitably mounted within the enclosed chamber of said housing structure, driving means operatively connecting said electric motor assembly and said shaft, a finishing member mounted on said shaft and adapted to revolve therewith, a bracket suitably supported on said housing structure, a second bracket rotatably mounted in said first mentioned bracket, a slide member movably mounted on said second bracket, a third bracket supported on said slide member and provided with a slideway, a second slide provided with a slideway, a third slide member movably mounted in the slideway of said second slide member, a shaft revolvably supported by said third slide member, a frustum member mounted on said last mentioned shaft and adapted to revolve therewith, said frustum member being provided with a conical surface, an electric motor assembly supported by said third slide member, driving means operatively connecting said second electric motor assembly and said second mentioned shaft, means for adjusting the position of said second slide in a vertical plane to provide various operative positions of said frustum member, means for moving said third slide to provide various operative positions of said frustum member to and from the cylindrical member, a lever member pivotally supported on said third bracket, means for supporting the cylindrical member in a position between said finishing member and said frustum member, said last mentioned means being

supported on said lever member, and means for adjusting the pivotal position of said lever member to provide various positions of said cylindrical member.

5. 2. In a machine for finishing a cylindrical member, the combination of a slide member mounted to move in a horizontal plane, a second slide member mounted on said first mentioned slide member and adapted to move in a vertical plane, a third slide member mounted on said second slide member and adapted to move in a horizontal plane, a frustum member revolvably mounted on said third slide member and engaging said cylindrical member, a finishing wheel revolvably mounted and engaging said cylindrical member, a lever member pivotally mounted on said first mentioned slide member, means for supporting said cylindrical member on said lever member, and an adjusting means pivotally mounted on said first mentioned slide member and engaging said lever member to provide means for adjusting the position of said cylindrical member.

25. 3. In a machine for finishing a cylindrical member, the combination of a revolvably mounted shaft member, a nut member engaging and adapted to adjustably actuate said revolvably mounted shaft in different adjusted positions, a slide member mounted on said revolvably mounted shaft to move in a horizontal plane, a second slide member mounted on said first mentioned slide member and adapted to move in a vertical plane, a third slide member mounted on said second slide member and adapted to move in a horizontal plane, a frustum member revolvably mounted on said third slide member and engaging said cylindrical member, a finishing wheel revolvably mounted and engaging said cylindrical member, a lever member pivotally mounted on said first mentioned slide member, means for supporting said cylindrical member on said lever member, and an adjusting means pivotally mounted on said first mentioned slide member and engaging said lever member to provide means for adjusting the position of said cylindrical member.

40. 4. In a machine for finishing a cylindrical member, the combination of a revolvably mounted shaft member, a nut member engaging and adapted to adjustably actuate said revolvably mounted shaft in different adjusted positions, a slide member mounted on said revolvably mounted shaft to move in a horizontal plane, a second slide member mounted on said first mentioned slide member and adapted to move in a vertical plane, a third slide member mounted on said second slide member and adapted to move in a horizontal plane, a frustum member revolvably mounted on said third slide member and engaging said cylindrical member, a finishing wheel revolvably mounted and engaging said cylindrical member, a lever member pivotally mounted on said first mentioned slide member, means for supporting said cylindrical member on said lever member, and an adjusting means pivotally mounted on said first mentioned slide member and engaging said lever member to provide means for adjusting the position of said cylindrical member, and means for clamping said revolvably mounted shaft in different adjusted positions.

45. 5. In a machine for finishing a cylindrical member, the combination of a structure provided with a bracket portion provided with a bore, a shaft member adjustably supported by said bracket portion and engaging the bore thereof,

a horizontal slide member movably supported on said shaft member, a vertical slide member movably supported on said horizontal slide member, a second horizontal slide member movably mounted on said vertical slide member, a frustum member operatively mounted on said second horizontal slide member and engaging said cylindrical member, means for supporting said cylindrical member, and a finishing member revolvably mounted on said structure and engaging said cylinder member. 5

10. 6. In a machine for finishing a cylindrical member, the combination of three slide members movably mounted, two of said slide members being movably supported by the remaining slide member, said last mentioned slide members comprising a horizontal slide member mounted on a vertical slide member, a frustum member operatively mounted on said horizontal slide member and engaging said cylindrical member, means for supporting said cylindrical member, and a finishing member operatively mounted and engaging said cylindrical member. 15

20. 7. In a machine for finishing a cylindrical member, the combination of a slide member adjustably mounted to move in a horizontal plane, a bracket member provided with an upstanding flange having a slideway therein and extending substantially in a vertical plane, a second slide member adjustably mounted in the slideway of said bracket member, said second slide member being further provided with a flange portion having a slideway extending substantially in a horizontal plane, a third slide member adjustably mounted in the slideway of said second slide member, a frustum member operatively supported on said third slide member and engaging said cylindrical member, means for supporting said cylindrical member, and a finishing member revolvably mounted and engaging said cylindrical member. 25

30. 8. In a machine for finishing a cylindrical member, the combination of three slide members movably mounted, said slide members comprising a horizontal slide member supporting a vertical slide member, said vertical slide member supporting a second horizontal slide member, a bracket member mounted on said first mentioned slide member, a frustum member operatively mounted on the third slide member and engaging said cylindrical member, means for supporting said cylindrical member, a finishing member operatively mounted and engaging said cylindrical member, and lever means for adjusting said means for supporting said cylindrical member to provide different positions of said cylindrical member, said last mentioned means being pivotally mounted on said bracket member. 35

40. 9. In a machine for finishing a cylindrical member, the combination of a plurality of slides movably mounted upon one another, a frustum member operatively mounted upon the uppermost of said slide members and engaging said cylindrical member, a lever member pivotally mounted on one of said slide members and supporting said cylindrical member, a second lever member pivotally mounted on one of said slide members and adapted to adjustably engage said first mentioned lever member to position said cylindrical member in different positions, and a finishing member mounted and engaging said cylindrical member. 45

45. 10. In a machine for finishing a cylindrical member, the combination of three slide members movably mounted upon one another, the upper-

most and lowermost slide members being adapted to move in parallel horizontal planes and substantially at right angles to the axis of said cylindrical member, the intermediate slide member being adapted to support the uppermost slide member and to move in a vertical plane, a frustum member operatively mounted upon the uppermost of said slide members and engaging said cylindrical member, a lever member pivotally mounted on one of said slide members and supporting said cylindrical member, a second lever member pivotally mounted on one of said slide members and adapted to adjustably engage said first mentioned lever member to position said cylindrical member in different positions, and a finishing member revolvably mounted and engaging said cylindrical member.

11. In a machine for finishing a cylindrical member, the combination of a slide member movably mounted to move in a horizontal plane, a bracket member mounted on said slide member and having an upright flange provided with a slideway together with a boss portion at the upper end thereof, said boss portion being provided with a bearing bore, a second slide member movably mounted in the slideway of said upright flange and provided with a horizontal slideway, a shaft member revolvably mounted in the bearing bore of said boss portion of said upright flange and retained against longitudinal movement, said shaft member engaging and actuating said second slide member, a third slide member movably mounted in the slideway of said second slide member, a frustum member operatively mounted on said third slide member and engaging said cylindrical member, a finishing member revolvably mounted and engaging said cylindrical member, and means for supporting said cylindrical member.

12. In a machine for finishing a cylindrical member, the combination of a slide member movably mounted to move in a horizontal plane, a bracket member mounted on said slide member and having an upright flange provided with a slideway together with a boss portion at the upper end thereof, said boss portion being provided with a bearing bore, a second slide member movably mounted in the slideway of said upright flange and provided with a horizontal slideway, a shaft member revolvably mounted in the bearing bore of said boss portion of said upright flange and retained against longitudinal movement, said shaft member engaging and actuating said second slide member, a third slide member movably mounted in the slideway of said second slide member, a frustum member operatively mounted on said third slide member and engaging said cylindrical member, a finishing member revolvably mounted and engaging said cylindrical member, and means for supporting said cylindrical member, means for adjusting said first mentioned slide member in different positions in a vertical plane.

13. In a machine for finishing a cylindrical member, the combination of a slide member movably mounted to move in a horizontal plane, a bracket member mounted on said slide member and having an upright flange provided with a slideway together with a boss portion at the upper end thereof, said boss portion being provided with a bearing bore, a second slide member movably mounted in the slideway of said upright flange and provided with a horizontal slideway, a shaft member revolvably mounted in the bearing bore of said boss portion of said up-

right flange and retained against longitudinal movement, said shaft member engaging and actuating said second slide member, a third slide member movably mounted in the slideway of said second slide member, a frustum member operatively mounted on said third slide member, and engaging said cylindrical member, a finishing member revolvably mounted and engaging said cylindrical member, means for supporting said cylindrical member, means for adjusting said first mentioned slide member in different positions in a vertical plane, said means for supporting said cylinder member being pivotally mounted, and a pivotally mounted lever member adapted to adjustably position said last mentioned means to position said cylindrical member in different positions.

14. In a machine for finishing a cylindrical member, the combination of a frustum member revolvably mounted and engaging the cylindrical member, a finishing member revolvably mounted and engaging the cylindrical member, a plate member suitably mounted and supporting the cylindrical member, a pair of brackets secured to said plate member and each provided with a bore, a shaft rotatably mounted in the bores of said pair of brackets and provided with an upturned portion, an arm member adjustably mounted on the upturned portion of said shaft, a bearing assembly rotatably supported on said arm member and provided with an outer race member revolvably engaging the cylindrical member, a second arm member secured to said shaft and adapted to rotate therewith, a third bracket secured to said plate member, a stud swivelly mounted in said second arm member and extending through said third bracket, and a resilient member mounted on said stud and adapted to exert a thrust against said third bracket to force said outer race of said bearing assembly to engage the cylindrical member.

15. In a machine for finishing a cylindrical member, the combination of a frustum member revolvably mounted, a horizontal slide member supporting said frustum member, a vertical slide member supporting said horizontal slide member, a second horizontal slide member supporting said vertical slide member and said first mentioned slide member together with said frustum member, said second horizontal slide member being provided with a pair of bores, shaft members fixedly secured in each of said bores of said second horizontal slide member, a lever member pivotally mounted on one of said shaft members and supporting said cylindrical member, a second lever member pivotally mounted on one of said shaft members and adjustably connected with said first mentioned lever member, a finishing member revolvably mounted and engaging said cylindrical member, and means for adjusting said second horizontal slide member together with its supported members in a vertical plane.

16. In a machine for finishing a cylindrical member, the combination of a movably mounted member engaging said cylindrical member to move said cylindrical member longitudinally past said movably mounted member, a plate member suitably mounted and having an edge surface adjacent said cylindrical member and provided with means for engaging and supporting said cylindrical member, a finishing member revolvably mounted and engaging said cylindrical member, a pair of brackets supported by said plate member, a shaft rotatably mounted in said

pair of brackets and provided with a bent portion, a third bracket slidably mounted on said bent portion of said shaft, means for locking said third bracket in a fixed position on said bent portion of said shaft, a stud supported in said third bracket, a bearing assembly mounted on said stud and provided with an outer race member rotatably mounted and engaging said cylindrical member to maintain said cylindrical member in engagement with said movably mounted member with uniform pressure.

17. In a machine for finishing a cylindrical member, the combination of a movably mounted member engaging said cylindrical member to move said cylindrical member longitudinally past said movably mounted member, a plate member suitably mounted and having an edge surface adjacent said cylindrical member and provided with means for engaging and supporting said cylindrical member, a finishing member revolvably mounted and engaging said cylindrical member, a pair of brackets supported by said plate member, a shaft rotatably mounted in said pair

of brackets and provided with a bent portion, a third bracket slidably mounted on said bent portion of said shaft, means for locking said third bracket in a fixed position on said bent portion of said shaft, a stud supported in said third bracket, a bearing assembly mounted on said stud and provided with an outer race member rotatably mounted and engaging said cylindrical member to maintain said cylindrical member in engagement with said movably mounted member with uniform pressure, a lever arm mounted on said shaft and adapted to rotate therewith, a fourth bracket mounted on said plate member and provided with a flange adjacent said lever arm, a second stud provided with a ball end 15 swivelly mounted in said lever arm, said second stud extending through said flange of said fourth bracket, and resilient means mounted on said second stud and exerting a thrust against said flange of said fourth bracket to move said outer race of said bearing assembly to engage said cylindrical member with said uniform pressure.

GUSTAVE A. CARLSON.
